UNITED STATES PATENT OFFICE.

THOMAS ANDREW, OF ROCHDALE, ENGLAND.

YARN PACKAGE AND THE LIKE AND METHOD AND MECHANISM FOR WINDING IT.

1,400,403.

Specification of Letters Patent.

Patented Dec. 13, 1921.

Application filed April 14, 1920. Serial No. 373,950.

To all whom it may concern:

Be it known that I, THOMAS ANDREW, a subject of the King of the United Kingdom of Great Britain and Ireland, and resident 5 of 492 Manchester road, Rochdale, in the county of Lancaster, England, have invented new and useful Improvements in Yarn Packages and the like and Methods and Mechanism for Winding Them, of which the 10 following is a specification.

The object of this invention is to make more easy, convenient and expeditious than it has hitherto been the attachment of the last wound end of the yarn of one yarn 15 package to the first wound end of another for the placing of yarn packages one after another in creels with the beginning of each attached to the end of another and the continuous running off or unwinding 20 of one yarn package after another. To this end, the invention consists in a method and means for winding yarn packages, which are provided with securely fixed coils wound on the yarn holders, previously to 25 the ordinary windings or coils at the first wound portions of the formation in ring spinning machines, ring doubling machines and other machines having ring rails or other yarn guiding means moved like ring rails.

30 In the accompanying drawings Figure 1 is a diagrammatic side elevation of the lower part of a bobbin with yarn wound upon it below and previously to the ordinary windings forming the bottom of the 35 bobbin and Figs. 2 and 3 are respectively a side elevation and a transverse section of a portion of a ring spinning machine sufficient for the illustration of the mechanism provided according to this invention. Fig. 4 is a detail of the sector and its 40 adjacent mechanism.

Fig. 1 shows an end 1 of yarn led to the 45 yarn holder, as secured in position by a downwardly wound coil 3 being first wound on the yarn holder 2 and then an upwardly wound coil 4 being wound over it and the end 5 of yarn extending from the upwardly wound coil 4 being led to and wound in the "bottom" 6 of the ordinary windings of 50 yarn on the yarn holder 2. By a suitable number of turns being included in the downwardly and upwardly wound coils 3 and 4 any length of yarn requisite may be provided for facilitating the connection of the 55 end first wound upon one yarn holder to the end last wound upon another in order that

the yarn holders may be mounted in creels and unwound successively in the manner hereinbefore mentioned. By the ends 1 and 5 of yarn being secured respectively 60 by the coils 3, 4 and by the ordinary windings of the "bottom" 6 of the yarn package on the yarn holder 2, the coils 3, 4 are themselves secured in position on the yarn holder 2 so that the end 1 is kept in position to be found easily and the length of 65 yarn for the connection of one yarn package to another is retained on the yarn holder 2 and preserved from unwinding or breakage in the handling or carriage of 70 the yarn packages until required for use. Coils or windings of opposite hand are wound one to overlap another on yarn 75 holders previously to the commencement of the coils or windings of the bottoms or like parts of yarn packages, such as bobbins, so as to be on parts of the yarn holders to project from the completed yarn packages at the ends at which winding was begun, so that the earlier wound coil or winding 80 secures the end of yarn first led to the yarn holder and is itself secured by a later coil or winding of opposite hand and the last overlapping coil is secured by the yarn forming its end portion extending into the 85 bottom or like basal part of the yarn package.

The winding of the coils or windings of 90 opposite hand on portions of yarn holders to project from the ends of yarn packages where the winding thereof begins may advantageously be effected after empty yarn packages have been applied to spindles on which coils or windings have been wound in the ordinary way preparatory to the doffing or removal of completed yarn packages. 95

Further according to this invention and as an example of the way of carrying it into effect, the usual device which is movable for lowering a ring rail in order that yarn 100 may be wound on spindles below the bottoms of yarn packages, is employed and made to occupy for a short time prior to the commencement of the bottoms or like parts of yarn packages, a position intermediate 105 between that in which windings on the spindles below the yarn holders is effected and the position occupied by it for winding of yarn packages.

As shown in Figs. 2 and 3, the usual 110 toothed sector 7 with a pulley 8 guiding a chain 9 used in working the ring rail 10

and movable into one position for winding of yarn onto yarn holders in the winding or formation of yarn packages in the ordinary way and into another position for yarn to be wound on spindles below the bottoms 6 of yarn holders in preparation for the removal of completed yarn packages, is contrived to be put for a time in an intermediate position for yarn to be wound on the 10 yarn holders below where the bottoms 6 of yarn packages are to be formed in the ordinary working of the ring rail 10.

To enable the sector 7 to be put into the intermediate position it is provided with a 15 dog or projection 12 with two places 13, 14 for engagement with the catch 15 which serves ordinarily for holding the sector 7 in position for the winding to proceed in the ordinary way.

20 The catch 15 is shown as a pivoted lever with a second arm 16 to arrive on the bracket or part 17 on which the catch 15 is mounted and so to prevent the catch 15 from escaping from the dog or projection 12 by movement in the direction indicated by the arrow 18. The catch 15 is shown as projecting rearwardly in Fig. 2 as a hook to act as a stop for a projection 20 formed on the sector 7 so as to prevent such sector 7 from 25 being wound too high. When the sector 7 is in an intermediate position it is preferable that the cam 21 for effecting the upward and downward movement of the ring rail 10 should be brought to rest in a desired 30 position such that in further movement it will first lower and then raise the ring rail 10. For this to be done in the case illustrated, the cam 21 is provided with a striking part 22 shown as a stud or projection in a suitable position and a lever 23, 35 with a treadle 24 and a projection 25 preferably adjustable, which by depression of the treadle 24 can be brought into the path of the striking part 22, is connected by a rod 26 to a lever 27 made so to work an engageable and disengageable clutch 28 ordinarily serving to transmit motion to the cam 21 that when the treadle 24 is depressed the clutch 28 is disengaged to allow the cam 40 45 50 55 60 65 70 75 80 85 90 95 100 10400 10405 10410 10415 10420 10425 10430 10435 10440 10445 10450 10455 10460 10465 10470 10475 10480 10485 10490 10495 10500 10505 10510 10515 10520 10525 10530 10535 10540 10545 10550 10555 10560 10565 10570 10575 10580 10585 10590 10595 10600 10605 10610 10615 10620 10625 10630 10635 10640 10645 10650 10655 10660 10665 10670 10675 10680 10685 10690 10695 10700 10705 10710 10715 10720 10725 10730 10735 10740 10745 10750 10755 10760 10765 10770 10775 10780 10785 10790 10795 10800

- Then while the catch 15 is engaged with the surface 14, it is ascertained by the observation of the position of the ring rail 10 or the position of the cam 21 or the bowl 35 that the arc 42, 43, 44 is presenting to the bowl 35 a part between the part 42 of largest diameter and the part 43 to be against the bowl 35 when the stud 22 comes against the striking part 20. The treadle 24 is then depressed and held so depressed until the cam 21 has brought the striking part 22 against the projection 25 and then the treadle 24 is released so that the clutch 28 may become engaged again. Then the ring spinning machine is started and as the spindles 11 begin to revolve, the cam 21 first lowers and then raises the ring rail 10 so as to wind yarn first in a descending spiral and then in an ascending spiral on the yarn holders 2 below the place at which the ordinary bottoms 6 of the yarn packages will eventually be wound. Then the handle 40 is turned again to raise the sector 7 and the catch 15 is brought into engagement with the surface 13 of the dog or projection 12 and the formation of the ordinary bottoms 6 of the yarn packages on the yarn holders 2 and the rest of the winding of yarn thereon proceeds in the ordinary way.
- When a ring spinning machine is first being put to work the roving to be twisted into yarn may be brought into connection with the spindles or the yarn holders as in the ordinary way of first putting such a machine to work and the commencement of winding of yarn below the place at which the windings to form the "bottoms" of yarn packages are to be wound on yarn holders may then proceed as in the manner hereinbefore described.
- If in any case there is no provision or occasion for yarn to be wound on spindles below the bottoms of yarn holders thereon, yarn may be attached to the yarn holders and be wound thereon in a manner similar to that hereinbefore described below the place at which the ordinary bottoms of the yarn packages are to be formed in a manner similar in other respects to that hereinbefore described.
- Similarly yarn may be wound upon yarn holders of forms other than those shown.
- This invention may be applied to ring doubling machines and to other machines having yarn guiding means of other forms moved like ring rails in a manner similar to that in which it is applied in ring spinning machines.
- What I do claim as my invention and desire to secure by Letters Patent is:—
1. The method of winding coils of yarn on yarn holders prior to forming yarn packages thereon which consists in winding securely fixed overlapping coils of yarn on the holders previously to the ordinary initial windings of the yarn packages and on parts of the holders to project from the first wound ends of completed yarn packages.
  2. The method of winding coils of yarn on yarn holders prior to forming yarn packages thereon which consists in winding yarn in overlapping coils in spirals of opposite hand on the holders previously to the ordinary initial coils of the yarn packages and on parts of the holders to project from the first wound ends of completed yarn packages. 70
  3. The method of winding coils of yarn on yarn holders prior to forming yarn packages thereon in a machine having yarn guiding means moved like a ring rail, according to which the yarn guiding means is set and made to work for a time in position for winding overlapping coils of yarn on parts of the yarn holders to project from the first wound ends of completed yarn packages. 80
  4. The method of winding coils of yarn on yarn holders prior to forming yarn packages thereon in a machine having spindles 90 and having yarn guiding means moved like a ring rail, according to which the device movable for putting the yarn guiding means in position for yarn to be wound on spindles in positions clear of the yarn holders 95 thereon is put for a time in a position intermediate between that position and the position in which it is placed for winding of yarn into yarn packages in the ordinary way. 100
  5. A machine as herein set forth for winding yarn into yarn packages on yarn holders on spindles, having yarn guiding means moved like a ring rail and means by which the yarn guiding means may be set and 105 made to work for a time and first in one direction and then in the opposite direction through a range of motion in position for winding coils of yarn on parts of yarn holders on the spindles to project from the first 110 wound ends of completed yarn packages.
  6. A machine as herein set forth for winding yarn into yarn packages on yarn holders, having yarn guiding means moved like a ring rail, means by which the yarn guiding means may be set and made to work for a time first in one direction and then in the opposite direction through a range of motion in position for winding coils of yarn on parts of holders on the spindles to project from the first wound ends of completed yarn packages, a cam for effecting the movements of the yarn guiding means and means by which the cam can be brought to rest in a desired position. 115
  7. A machine as herein set forth for winding yarn into yarn packages on yarn holders on spindles having yarn guiding means moved like a ring rail, a device movable for putting the yarn guiding means in position 120
  - 65 125
  - 65 130

for yarn to be wound on the spindles in positions clear of the yarn holders thereon, having an engaging part presenting two places of engagement for a catch and a catch for engagement therewith, the one place of engagement serving for engagement of the catch to hold the device in position for winding to proceed in the ordinary way and the other place of engagement serving for engagement of the catch to hold the device in position for yarn to be wound previously to the initial windings of yarn packages on parts of the holders to project from completed yarn packages.

8. A machine as herein set forth for winding yarn into yarn packages on yarn holders on spindles, having yarn guiding means moved like a ring rail, a device movable for putting the yarn guiding means in position for yarn to be wound on the spindles in positions clear of the yarn holders thereon, having an engaging part presenting two places of engagement for a catch and a catch for engagement therewith, the one place of engagement serving for engagement of the catch to hold the device in position for winding to proceed in the ordinary way and the other place of engagement serving for engagement of the catch to hold the device in position for yarn to be wound previously to the initial windings of yarn packages on parts of the holders to project from completed yarn packages, a cam for effecting the movement of the yarn guiding means, means for driving the cam, and means for bringing the cam to rest in one position and connected means for bringing the cam into and out of connection with means for driving it.

9. A machine as herein set forth for winding yarn into yarn packages on yarn holders on spindles, having yarn guiding means moved like a ring rail, a device movable for putting the yarn guiding means in position for yarn to be wound on the spindles in positions clear of the yarn holders thereon, having an engaging part presenting two places of engagement for a catch and a catch for engagement serving for engagement of the catch to hold the device in position for wind-

ing to proceed in the ordinary way and the other place of engagement serving for engagement of the catch to hold the device in position for yarn to be wound previously to the initial windings of yarn packages on parts of the holders to project from completed yarn packages, a cam for effecting the movement of the yarn guiding means and furnished with a striking part, means for driving the cam, a movable stop to be interposed in the path of the said striking part and means in connection with the stop for bringing the cam into and out of connection with the means for driving it.

10. A machine as herein set forth for winding yarn into yarn packages on yarn holders on spindles, having yarn guiding means moved like a ring rail, a device movable for putting the yarn guiding means in position for yarn to be wound on the spindles in positions clear of the yarn holders thereon, having an engaging part presenting two places of engagement for a catch and a catch for engagement therewith, the one place of engagement serving for engagement of the catch to hold the device in position for winding to proceed in the ordinary way and the other place of engagement serving for engagement of the catch to hold the device in position for yarn to be wound previously to the initial windings of yarn packages on parts of the holders to project from completed yarn packages, a cam for effecting the movement of the yarn guiding means and furnished with a striking part, means for driving the cam, an engageable and disengageable clutch in the means for driving the cam, a lever with a movable stop to be interposed in the path of the said striking part and means in connection with the lever for bringing the clutch into and out of engagement.

In testimony that I claim the foregoing as my invention, I have signed my name in presence of two witnesses, this thirtieth day of March, 1920.

THOMAS ANDREW.
